UNITED STATES PATENT OFFICE.

GEORGE BEACOCK AND TERENCE SPARHAM, OF BROCKVILLE, ONTARIO,
CANADA.

ARTIFICIAL LIMB.

SPECIFICATION forming part of Letters Patent No. 329,880, dated November 10, 1885.

Application filed August 3, 1885. Serial No. 173,368. (No model.)

To all whom it may concern:

Be it known that we, GEORGE BEACOCK and TERENCE SPARHAM, citizens of Canada, residing at Brockville, in the Province of Ontario, Canada, have invented certain new and useful Improvements in Artificial Limbs, of which the following is a specification, reference being had to the accompanying drawings.

This invention has relation to artificial limbs; and it consists in certain features of construction hereinafter described, and particularly pointed out in the claims.

Referring to the drawings, Figure 1 is a side elevation of an arm. Fig. 2 is a side elevation of a leg, each embodying features of our invention; and Figs. 3, 4, 5, 6 are details hereinafter described.

Like letters of reference indicate like parts in all the figures of the drawings.

A represents a shoulder-cap, which may be formed of leather, rawhide, rubber, or other suitable material, so as to fit upon the shoulder and serve as a part for the pivotal connection therewith of the arm. The cap A is formed like a hood, with the rear side, A', thereof broader than its front side, and is provided at the end with a slot, A², (see Fig. 3,) in which the connecting-bolt B is inserted, so that the arm C is supported at its upper end pivotally, in order that it may swing in a manner similar to the movement of the natural arm. Most of the natural movements of the shoulder being forward, the front of the cap is made narrower, to avoid forcing its edge into the breast of the wearer, while for firmness of situation, the rear portion of the cap is left as broad as possible, so that the weight and conformation of the clothes of the wearer may act upon the cap to hold the same in place. The object of the slot A² is that the cap may be upwardly inclined at its free end, to facilitate placing it in position upon the shoulder. The general outline of the end being circular, the movement of the cap against the inner surface of the upper end of the arm is such as to upwardly incline the cap and facilitate its being placed in position upon the shoulder, as well as to facilitate the removal of the cap from the shoulder without necessitating unnatural or difficult movement of the body or arm.

The upper portion of the arm, and also the upper portion, D, of the leg, embodying our invention, are made hollow. In this instance we have selected rawhide as the material. At 55 a point within the upper portion of the arm or leg we insert a partition, C' or D', in order to form an air-chamber, and communicating with said chamber is an aperture covered by a valve, C² or D², which opens outwardly and 60 closes inwardly against the leg or arm to prevent the entrance of air through said aperture into said chamber. By providing such a chamber and valve, the insertion of a stump therein forces the air therefrom and out 65 through said aperture, so that a vacuum is formed within the arm or leg and the same held in position upon the stump by the pressure of the atmosphere.

When it is desired to remove the leg or arm 70 thus constructed, it is only necessary to lift the valve, when entrance of the air will allow an easy removal of the stump. This feature of atmospheric pressure as a means for retaining the artificial limb upon the stump we consider an important feature of our invention, and do not limit ourselves to the exact construction of valves herein shown or herein-after described, or to any particular formation of the air-chamber.

E represents the pivotal bolt employed at the joints, and said bolt may be constructed of any desired material—such as rawhide or metal—and may extend completely through from side to side of sections of an arm or leg, 85 or may consist of separate short bolts passing only through the material at each side of said sections. The joint employed herein consists of a hollow sphere, F, having a projection, F', one face, F², of which is adapted to bear against 90 the inner walls of an adjacent section whenever that section having said spherical part is at substantially a right angle to said other section. The said projection F' is at the opposite side concaved, as at F³, so that when the sections are substantially in line with each other said concavity F³ may come in contact with the inner walls of the adjacent and pivoted section of the limb.

By the projection F' having the faces described we insure a firm bearing of the sections which are pivoted upon each other when

swung to the extreme in either direction. The upper portion of the leg or arm is concaved, as at F⁴, and proportioned with relation to the pivot, so as to bear upon the upper edge of 5 the lower section and at the inside of the joint, whereby two points of contact are provided when the sections are at substantially a right angle to each other—namely, the faces F² and the concavity F⁴.

10 The valve C² may be of any desired construction. In this instance it is simply a piece of leather or other flexible material secured by rivets or stitches C³ to the body portion D or C of the limb, the said valve being creased or weakened or otherwise constructed at C⁴ to 15 form a hinge-line for the same.

15 G represents the thumb of the hand portion of the arm, the same being formed to project inwardly into the hollow hand or wrist portion, where a spring of suitable construction 20 is employed to normally hold the end of the thumb in contact with the end of the first finger. The thumb and hand portion is perforated, the latter at the points G', for the passage there- 25 through of a rawhide strip, strap, or thong, H, which is round in cross-section at its middle portion and flattened and gradually thinned down to its ends, as clearly shown in Fig. 4, so that when wet and inserted through the 30 hand portion and through the thumb it may be drawn snugly against the former and inserted into the hole G' beneath the thumb, as clearly shown in Fig. 5, and its ends turned or clinched, whereby when said thong dries 35 and hardens it becomes rigid and forms a serviceable pivot and a strong means for securing the thumb to the hand.

Although in this instance we construct the several sections of the limbs of rawhide, still

we do not confine our invention to the use of 40 that material, as several features thereof are capable of being used in connection with artificial limbs made of other substances.

Having described our invention and its operation, what we claim, and desire to secure 45 by Letters Patent, is—

1. In combination with an arm, the cap-piece A, formed to fit the shoulder, and having its rear side broader than its front side, substantially as specified. 50

2. The combination, with an arm and its supporting-bolt, of a cap-piece formed to fit the shoulder, and slotted at its end, substantially as specified.

3. A joint comprising a sphere having a 55 projection, as F', with adjacent faces F² and F³, adapted and arranged to come in contact with the opposite and inner surfaces of an adjacent section, substantially as specified.

4. In an artificial limb, a strip, strap, or 60 thong of rawhide arranged as a pivotal member of a joint, substantially as specified.

5. A strip, strap, or thong of rawhide, cylindrical in cross-section at a portion thereof, designed for a pivot, and flattened or thinned 65 at a portion thereof, whereby it is adapted to be wound and fastened, substantially as specified.

6. In an artificial limb, an air-chamber provided with a valve, substantially as specified. 70

In testimony whereof we affix our signatures in presence of two witnesses.

GEORGE BEACOCK.
TERENCE SPARHAM.
